CURTAIN ROD BRACKET

Bruno E. Sliwa, Chicago, Ill.

Application March 23, 1939, Serial No. 263,590

3 Claims. (Cl. 156—22)

The present invention relates to curtain rod brackets and has for its main object the provision of a bracket wherein one end of a curtain rod may be hingedly pivoted so that upon lifting of the opposite end of the rod from its co-operating bracket, the rod may angularly shift downwardly for the purpose of placing thereon a curtain, drapery or other fabric hanging, without the necessity of lifting off the entire rod from both brackets.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views;

Fig. 1 is an elevational view of a window with the curtain rod and its co-operating brackets in position upon the window frame;

Fig. 2 is an enlarged top-plan elevational view of a curtain rod with a pair of co-operating brackets;

Fig. 3 is an elevational side view of the bracket constituting the subject matter of this application, the view having been taken along line 3—3 of Fig. 2;

Fig. 4 is an elevational side view of the opposite bracket;

Fig. 5 is a cross-sectional view of the curtain rod bracket of the form shown in Fig. 3 with a curtain rod bracket in an operative position therewith;

Fig. 6 is a top elevational view of a bracket of a modified construction showing one end of a curtain rod in an operative position therewith;

Fig. 7 is an end elevational view of the curtain rod bracket of the modified form shown in Fig. 6;

Fig. 8 is a top-plan view of the curtain rod bracket of another modified construction; and

Fig. 9 is an end cross-sectional view through the bracket, taken substantially on line 9—9 of Fig. 8.

Referring to the present drawing in detail the preferred form of the invention illustrated in Figs. 2, 3 and 5, includes leaf 10 adapted to be attached to window frame 11. Rigidly formed with and perpendicularly extending from said leaf 10 is plate 12 which supports a pair of cup members 13, the latter being either soldered or

otherwise rigidly affixed to said plate 12. Each of said members 13 is provided at its lower end with a cross plate 14 for strengthening the structure of each of said members 13. Each of said members 13 is further provided with a vertical slot 15 through which one end of curtain rod 16 is insertable within cup member 13. The end of said rod 16 which is insertable within the cup member 13 through said slot 15 is provided with a rigidly formed ball 17, the diameter of which may be either equal to the diameter of the cup-shaped member 13 or if preferred may be smaller than the latter. Said ball 17 constitutes an engaging means for the adjacent end of rod 16 with cup member 13, preventing said end of rod 16 from withdrawing from said member 13, but at the same time permitting vertical pivotal movement of the rod with respect to said member 13.

Slot 15 does not extend throughout the entire length of said member 13, but terminates short of the lower end thereof, effecting a marginal strip in transverse relation with respect to slot 15 upon which rod 16 is adapted to rest and which prevents further downward shifting movement of said rod 16, as is clearly seen in Fig. 3.

Slots 15 in the cup members 13 are at an angle with respect to the said supporting plate 12, necessitating elbow 18 in rod 16.

The opposite free end of rod 16 is adapted for positioning upon a conventional bracket 19. Said latter bracket includes an affixing plate 20 with which said bracket 19 is rigidly formed and from which the same projects at a right angle. Said bracket 19 further includes a pair of slots 21 within which the free end of one or two of rods 16 may fit.

When a curtain or other fabric hanging is required to be placed upon rod 16 or taken off therefrom, the free end of said rod 16 is taken off from its co-operating bracket 19, by lifting the same manually. This operation permits rod 16 to be pivotally shifted at its opposite end in its co-operating cup member 13 to assume the position shown by dotted lines in Figs. 1 and 5. When in that angular position the curtain or other fabric hanging may be placed upon rod 16 and thereupon the free end thereof may be lifted manually or by some suitable lifting tool to bracket 19. Thus from the hereinabove description it will be apparent that the employment of a step-ladder to lift rod 16 off its brackets or to place the same thereon is entirely eliminated.

The modified form of the invention illustrated

in Figs. 6 and 7 contemplates a bracket of modified form which includes an affixing leaf 10' with supporting plate 12' rigidly affixed to the former. Said plate 12' is adapted to support 5 a cup member 13' having a transverse brace 14' at its lower end, and a vertical oblong slot 15'. If preferred, said plate 12' may be rigidly formed with the cup member 13', so that in the process of making of the bracket plates 10', 12' and cup 10 member 13', may be formed out of a single plate by suitably bending the same, as is seen in Fig. 15. Said slot 15' is on a plane parallel to the affixing plate 10' or to the window frame. This modified structure of the bracket necessitates a modification of the construction of rod 16' which 20 is provided with a short stub end 22 in perpendicular relation with the body of rod 16'. This modified construction of the bracket illustrated in Figs. 6 and 7 will permit the bracket to be placed either at the right or left side of the window frame.

Figs. 6 and 7 illustrate the position of rod 16' when the bracket is affixed to the left side of the window frame. When the bracket is placed at 25 the right side of the window frame the position of rod 16' with respect to the bracket is shown by dotted lines in Fig. 6. Rigidly affixed to the stub end 22 of the rod is ball 17' placed within cup member 13' and the purpose and operation 30 of said ball 17' is the same as of ball 17 in the preferred form of the device.

A further modification of the bracket shown in Figs. 8 and 9 contemplates employment of a pair of cup members 23 affixed to the supporting 35 plate 12, the latter being rigidly formed with affixing plate 10. In this modified form of the invention cup members 23 have slots 24 at points which are on a plane parallel to the supporting plate 12 or on a plane perpendicular to the affixing plate 10 or to the window frame. This 40 bracket is adapted to receive rod 25 provided with a stub end 26 rigidly formed with the body of the rod 25. In this modified form of the device rod 25 and the stub end 26 are on a vertical plane 45 both in the operative position of rod 25 in conjunction with its two brackets and also when the same is lifted off by one of its ends from a co-operating bracket and shifted downwardly to an angular position illustrated by dotted lines in 50 Fig. 9. This modified form of the invention shown in Figs. 8 and 9 likewise includes ball 27 rigidly formed with the stub end 26 of rod 25. It will be further seen that when rod 25 is in an 55 operative position shown by full lines in Figs. 8 and 9, portion of the body of rod 25 enters within cup member 23 through slot 24. When however the free end of rod 25 is lifted from the opposite bracket, the rod shifts angularly, so that when it assumes its ultimate angular position with respect to the bracket shown in Figs. 8 and 9, the 60 stub end portion 26 thereof partially extends through slot 24 as is seen in dotted lines in Fig. 9.

It is further observed that when rods 16, 16' and 25 are of a diameter smaller than the width 65 of the respective slots 15, 15' and 24, then said rods may be shifted horizontally and obliquely in addition to the vertical shifting.

While there is described herein a preferred embodiment of the present invention, it is nevertheless to be understood that minor changes may be made therein without departing from the spirit and scope of the invention as claimed.

What I claim as new is:

1. The combination with a curtain rod having 75 a main straight portion, an angularly directed end

portion, and an enlarged ball fixed on the free end of said angularly directed end portion, of a supporting bracket for one end of said rod including an angular plate having a vertical attaching portion and a vertical portion extending at a right angle to and forwardly from said attaching portion, and a vertical cylindrical member rigid with said forwardly extending bracket portion and having a vertical slot opening through the top thereof but terminating above the bottom of 10 the same, said ball being fitted in said cylindrical member for universal movement therein, said rod extending through and being movable in said slot to permit vertical swinging movement of 15 said rod relative to said bracket from a horizontal curtain supporting position to a depending substantially vertical position when the other end of said rod is unsupported, and a further supporting bracket adapted to removably receive said other end of the rod and cooperating with 20 the first-named bracket for supporting said rod in the horizontal position.

2. The combination with a curtain rod having a main straight portion, an angularly directed end portion, and an enlarged ball fixed on the 25 free end of said angularly directed end portion, of a supporting bracket for one end of said rod including an angular plate having a vertical attaching portion and a vertical portion extending at a right angle to and forwardly from said 30 attaching portion, and a vertical cylindrical member rigid with said forwardly extending bracket portion and having a vertical slot opening through the top thereof but terminating above the bottom of the same, said slot being on a plane 35 parallel to the said vertical attaching portion of the bracket, said ball being fitted in said cylindrical member for universal movement therein, said rod extending through and being movable in said slot to permit vertical swinging movement 40 of said rod about the longitudinal axis of said angularly directed end portion and relative to said bracket from a horizontal curtain supporting position to a depending substantially vertical position when the other end of said rod is unsupported, and a further supporting bracket 45 adapted to removably receive said other end of the rod and cooperating with the first-named bracket for supporting said rod in the horizontal position, said angularly directed end portion of 50 the rod resting on the bottom wall of said vertical slot.

3. The combination with a curtain rod having a main straight portion, an angularly directed end portion, and an enlarged ball fixed on the 55 free end of said angularly directed end portion, of a supporting bracket for one end of said rod including an angular plate having a vertical attaching portion and a vertical portion extending at a right angle to and forwardly from said 60 attaching portion, and a vertical cylindrical member rigid with said forwardly extending bracket portion and having a vertical slot in one side thereof and opening through the top of the 65 same, said slot being on a plane perpendicular to the said vertical attaching portion of the bracket, said ball being fitted in said cylindrical member for universal movement therein, said rod extending through and being movable in said 70 slot to permit vertical swinging movement of said rod relative to said bracket from a horizontal curtain supporting position to a depending substantially vertical position when the other end of said rod is unsupported, and a further 75

supporting bracket adapted to removably receive said other end of the rod and cooperating with the first-named bracket for supporting said rod in the horizontal position, said angularly directed end portion of the rod being vertically movable downwardly into said slot when the rod

is swung to the depending position and being vertically movable upwardly out of said slot and to a vertical position within said cylindrical member when the rod is swung to the horizontal position.
